UNITED STATES PATENT OFFICE.

JOHN C. DORAN, OF DANBURY, CONNECTICUT.

SAFETY PIN.

1,413,396.

Specification of Letters Patent. Patented Apr. 18, 1922.

Application filed December 26, 1919. Serial No. 347,295.

To all whom it may concern:

Be it known that I, JOHN C. DORAN, a citizen of the United States, and a resident of Danbury, in the county of Fairfield and State of Connecticut, have invented an Improvement in Safety Pins, of which the following is a specification.

This invention relates to safety pins and the like. One of the objects thereof is to provide a device of the above nature of practical and inexpensive construction, and the action of which shall be dependable and effective. Another object is to provide a device of the above nature which shall possess a high degree of simplicity and strength. Other objects will be in part obvious and in part pointed out hereinafter.

The invention accordingly consists in the features of construction, combinations of elements and arrangement of parts which will be exemplified in the structure hereinafter described and the scope of the application of which will be indicated in the following claims.

25 In the accompanying drawings in which are shown one or more of various possible embodiments of the several features of this invention,

Figure 1 is a top plan view;

30 Figure 2 is a side elevation of the device shown in Figure 1;

Figure 3 is an enlarged sectional view taken along the line 3—3 of Figure 2;

Figure 4 is a similar view showing a modified cross-section; and

Figure 5 is a similar view showing another modification or cross-section.

Figure 6 is a similar view with another cross-section.

40 Similar reference characters refer to similar parts throughout the several views of the drawings.

Referring now to these drawings in detail, there is shown a pin formed of a single wire member which may be for the sake of cheapness constructed of round cross-section. This wire is pointed as at 10 and extends substantially straight although slightly bowed in an outward direction to form the pin proper, 11. Beyond the pin portion, the wire which is of resilient metal, is formed into the coil 12 which may have one or more convolutions although preferably a single turn is given to the wire. From the coil 55 portion the wire passes upwardly across the part 11, as best shown in Figure 1 of the

drawings, to form a guard 13 which performs functions hereinafter described in detail. From this guard the wire extends downwardly as at 14 and thence substantially parallel to the portion 11 to form a back 15. This back portion extends in a substantially straight line to a bend 16, flattened as at 16^a, which serves to guide the pin point and lock it in closed position. 60 After this bend or loop the wire is upwardly curved as at 17 and thence bent across the pin as shown at 18 in Figure 1 of the drawings. Following the portion 18 is a portion 19 extending parallel to the part 17 and, at 70 20, parallel to the back of the device. The end of the wire is curled about the part 15 to lock itself firmly in position as at 21.

Through the effective or free portion of the pin part 11 and back part 15, the wire 75 is forced into a flanged conformation. As it appears in Figures 1 and 2 of the drawings, the section of the wire at the above points is substantially as is shown in Figure 3. It is given flanges 23 and 24 which lie 80 in the plane of the device, that is, a plane including the portions 11 and 15. By this conformation, the parts 11 and 15 are greatly stiffened against bending in an outward or inward direction and are even somewhat 85 stiffened as against lateral bending, all as compared with a round wire of equal area of cross-section. As is well known, when a device of this nature fails in action, one or both of the portions 11 or 15 are bent in 90 such manner as to pull the point of the pin out of the catch within which it rests. This type of cross-section reduces to a minimum the chance of this bending action and is of 95 corresponding value. It is to be understood that certain of the features of this invention 100 might be attained with a pin constructed throughout of wire of uniform cross-section, but cost of construction is reduced by using round wire forced into a stiff cross-section at the points at which such cross-section is desired.

In Figure 4 of the drawings is shown another type of cross-section which may be given the portions 11 and 15. In this form 105 there is a web part 25 which connects the upper and lower flanges 26 and 27 respectively. In other words, it is of a general I-beam type of section.

In Figure 5 is another form of cross-section, this being assumed to be taken through the member 11 and an identical but

inverted section to be used with the member 15. In this section there is provided a flange part 28 which faces the inside of the pin and a central flange extension 29 extending 5 outwardly from the pin, both at the pin proper and at the back 15. The construction of Figure 6 is substantially the same as that of Figure 5 except that the flanges are omitted, giving a general oval cross- 10 section.

The functions of the above features of construction are as follows. The coil portion 12 by reason of the resilience of the metal, permits the pin 11 to be sprung throughout 15 the desired angular range, its outward movement being limited at the desired point by the guard part 13. The pin is so formed that it normally tends to maintain the position indicated in dotted lines at 30 in Figure 2 of 20 the drawings. It is closed in the usual way by pressing it inwardly until it rests within the catch or loop 17. In entering this position, however, it presses laterally the resilient lock 16 which springs into place directly 25 beneath it and prevents the accidental opening of the pin. It is removed by a combined inward and lateral pressure upon the pin member.

The guard portion 13 not only performs 30 the function of guiding the springing movement of the pin member but also, as its above name implies, prevents the wedging of the material with which the pin is used into the coil or coils 12. This function is of marked 35 value as there is a tendency of the cloth or other material to slip endwise into the crevices at the hinge end of the spring and become wedged in position with a likelihood of tearing.

40 It may here be noted that by the expression "active length" as used with regard to the pin member, is meant substantially that portion of the pin member which is intermediate the pin and catch and is liable to engagement with the material when the pin is 45 in use. This expression when used with regard to the back member of the pin denotes that portion of the back which is opposite the "active length" of the pin member.

50 It will thus be seen that there is provided a construction in which the several objects of this invention are achieved. The holding action of the pin is secure and dependable and the material protected against injury. 55 Furthermore, the cost of manufacture is reduced to a minimum. The several features, although co-acting in the complete device, are of independent value and the entire construction is well suited to meet the requirements of hard practical use.

As various possible embodiments might be made of the above invention and as various

changes might be made in the embodiment above set forth, it is to be understood that all matter herein set forth or shown in the 65 accompanying drawings is to be interpreted as illustrative and not in a limiting sense.

I claim as my invention:

1. In construction for safety pins and the like, a pin member having substantially 70 throughout its active length a diameter greater in the plane of the safety pin than in a plane transverse thereto.

2. In construction for safety pins and the like, a pin member shaped to present greater 75 stiffness against outward bending than against bending in a transverse direction.

3. In construction for safety pins and the like, a pin member provided with longitudinally extending flanges substantially 80 throughout its active length, said flanges comprising a pair which are oppositely directed and lie substantially in a single plane to give said pin member greater stiffness in the plane of the safety pin than in the direction transverse thereto.

4. In construction for safety pins and the like, in combination, a pin member and a back member, each shaped to present a greater stiffness in the plane in which they 90 lie than in a plane transverse thereto.

5. In construction for safety pins and the like, a pin member extended in cross section in the plane of the safety pin and blunter on its inner than upon its outer side.

6. In construction for safety pins and the like, a pin member provided with inwardly extending and outwardly extending flanges substantially throughout its active length, said flanges being shaped to give said pin 100 member a substantially greater stiffness in the plane of the safety pin than in a direction transverse thereto.

7. A safety pin formed of a single wire having a pin form provided at its central 105 part with longitudinal, dull-edged, stiffening flanges of a thickness at their outer parts materially less than the distance between those parts in a circumferential direction, with respect to the body of the pin.

8. In construction for safety pins and the like, in combination, a pin portion and a back portion formed of a single wire resiliently connected one with another, each of said portions being of flanged non-circular 115 cross section substantially throughout their active length and being shaped to have a stiffness greater in the plane of the safety pin than that of round wire of equal area of cross section.

In testimony whereof, I have signed my name to this specification this 11th day of December, 1919,

JOHN C. DORAN.
